UNITED STATES PATENT OFFICE.

EDWARD J. RAPPS, OF LOS ANGELES, CALIFORNIA.

COMBINATION SPRING MOVEMENT AND WASHING MACHINE.

Application filed November 2, 1923. Serial No. 672,298.

This invention relates to washing machines and has for its object to provide a spring power mechanism in which energy may be stored and transmitted to a tank or tub to swing same.

In operating the washing machine to give an oscillating movement, I utilize a spring motor which drives a pinion, the latter engaging a double faced arcuate rack so as to give an oscillating movement. A pair of oppositely positioned springs are operatively connected to the tub of the washing machine so that in opposite directions of oscillation the springs are alternately tensioned and react to swing the tub in the reverse direction. A fly wheel may be employed to store up the energy of rotation acting as a governor.

Other objects and advantages will be made manifest in the following specification of an embodiment of the invention illustrated in the accompanying drawing, wherein,

25 Fig. 1 is a plan of the machine.

Fig. 2 is a side elevation of the machine.

Fig. 3 is an end view.

Fig. 4 is a transverse section showing the reverse gear.

30 Fig. 5 is an end showing the reverse gear in reversing position.

Fig. 6 is a perspective of the reverse gear.

Fig. 7 is a detail of the auxiliary spring mechanism.

35 The present machine consists of a suitable tub 2 of the type to be swung from an upright to an inverted position and back so that laundry in the tub will be cascaded.

The tub is secured fast on a shaft 3 in 40 bearings 4. Fastened on the shaft is a block 5 having a transverse pivot 6 on which is mounted a semicircular gear 7 with teeth along each side and around its ends.

45 Perpendicularly to one side of the pivot 6 is a shaft 8 on which is secured a pinion 9, said shaft being mounted in bearings 11.

The gear 12, the shaft 8, the pinion 9 and the gear 7, connected to the shaft 3, constitute a reversing mechanism for oscillating the tub. The gear 7 is an endless semicircular rack which travels first on one side of the pinion 9 and then on the other side.

The gear 7 is held for mesh with the pinion 9; the block 5 limiting the swinging movement of the gear 7.

Fastened on the shaft 8 is a gear 12 meshing with a master gear 13 loosely mounted on a shaft 14 which is in line with the shaft 3. Fastened to the shaft 14 is the inner end of a spring 15 whose outer end is fastened at 16 to the wheel 13. On the shaft 14 is fastened a ratchet wheel 17 turning freely in one direction past a latch 18 Fig. 3. The shaft 14 is mounted in bearings 19 and fastened on the shaft is a hand wheel 20. Turning the hand wheel winds the spring 15 and the energy stored in the spring turns the gear wheel 13 and the gear 12 and the pinion 9. This will tilt the tank or tub from the position shown in Fig. 5 in the direction of the arrow *a* Figure 5, until the tub is completely inverted.

In the first quarter revolution of a tub most of the power is required and in the second quarter revolution much less power is required and means are employed to absorb the excess power from the spring 15 so as to aid in the reversing movement of the inverted tub 2.

Power conserving means are shown as including a fly wheel 25 fastened on a shaft 26 in bearings 27. On the shaft is fastened a pinion 28 and this meshes with a larger wheel 29 secured on the shaft 3 carrying the tub 2. Fastened on the shaft 3 is a double groove pulley or a pair of pulleys 30 and attached at opposite sides thereof are the upper ends of opposed springs 31 and 31^a, which springs are attached to anchors 32.

When it is desired to prepare the machine for operation, the tub 2 is manually rotated from the neutral position shown in Fig. 4 (when the main spring 15 is unwound) to a starting or filling position, as shown in Fig. 5. The tub is then hooked to hold the same in starting position until filled with clothes and water, etc., by a hook 33, one end of which is pivoted on the U-bolt 34 fixed to a standard 35, while the hook engages an eye-bolt 36 fixed to the tube 2. The main spring 15 is then wound up by means of the hand wheel 20 to any desired

tension, according to the length of time required to wash the clothes.

In order to start the machine, it is then only necessary to release the hook 33 from the eye-bolt 36.

In operation the spring 15, pulling constantly in one direction, turns the pinion 9 and this drives the gear 7 so as to invert the tub 2. As the effort by the spring 15 moves the tub 2 in a quarter turn the tub resistance is reduced and the excess energy is utilized in tensioning the springs 31 by winding them over its pulley 30. At the same time the energy of the spring 15 is stored in the fly wheel 25 which acts as a governor for the speed of operation of the machine. The other spring 31 operates to reverse the fly wheel and to reverse the motion of the tub 2 and the stored energy of the spring 31 also aids in initiating the reversal of the tub.

The inversion and the reversal of the tub is continuous and automatic so long as energy is stored in the spring 15 sufficiently to over-come the load.

It will be noted as shown in Fig. 1, that the segmental rack gear 7, mounted in the block 5 which is shown in Fig. 1, is formed with a recess, the sides of which engage the arms of the segmental gear and restrict the sidewise oscillation on the transverse pivot 6. This block and the various cooperating elements are designed so that the pinion 9 will remain in mesh with the teeth on opposite sides of the segmental gear 7. This gear 7 is shown as forming a semicircle, but it may be made of less or of greater arc if desired.

In the operation of washing, when the tub is in the starting position of Fig. 5, it will require considerable energy from the spring 15 to turn the device through the first quarter circle into the position of Fig. 4. When it is partially turned in the position of Fig. 4, the water will flow to the lowest part and the clothes will topple over, thereby giving an impetus which will allow the second quarter turn to be made without requiring so much driving power from the spring 15.

The springs 31 are brought into action alternately and operate by tension giving a pull on their respective pulleys to aid the returning of the tub and in the position of Fig. 7 both will be giving an equal and counter-balanced tension in opposite directions.

Further embodiments, modifications and

variations may be resorted to within the spirit of my invention.

What is claimed is: —

1. In a machine, an invertible tub, a spring mechanism to store energy, a reversing mechanism including a pinion and an endless semi-circular rack connected to the appliance and operative by the spring mechanism, and a speed controlling means.

2. In a machine, an invertible appliance, a spring mechanism to store energy, a reversing mechanism including a pinion and an endless semi-circular rack connected to the appliance and operative by the spring mechanism, and a speed controlling means, said means including an energy storing instrumentality.

3. In a machine, an invertible appliance, a spring mechanism to store energy, a reversing mechanism including a pinion and an endless semi-circular rack connected to the appliance and operative by the spring mechanism, and a speed controlling means, said means including an energy storing instrumentality comprising a fly wheel.

4. In a machine, an invertible appliance, a spring mechanism to store energy, a reversing mechanism including a pinion and an endless semi-circular rack connected to the appliance and operative by the spring mechanism, and a speed controlling means, said means including an energy storing instrumentality comprising springs.

5. In combination, an invertible wash tub, a shaft supporting the tub, a reversing mechanism including a pinion and an endless semi-circular rack attached to the shaft, a driving spring for the reversing mechanism, a power absorbing and storing means connected to the said shaft for absorbing excess energy of the driving spring after the initial resistance in tilting the tub is overcome.

6. In combination, an invertible wash tub, a shaft supporting the tub, a reversing mechanism including a pinion and an endless semi-circular rack attached to the shaft, a driving spring for the reversing mechanism, a power absorbing and storing means connected to the said shaft for absorbing excess energy of the driving spring after the initial resistance in tilting the tub is overcome, said means being operative to facilitate in reversing the tub.

In testimony whereof I have signed my name to this specification.

EDWARD J. RAPPS.
